UNITED STATES PATENT OFFICE.

JOSEPH SUTKAY, OF LAURENTS, LOUISIANA, ASSIGNOR OF ONE-THIRD TO ROSE LE DOUX, OF LAURENTS, LOUISIANA.

RAIL-JOINT.

1,158,332.

Specification of Letters Patent.

Patented Oct. 26, 1915.

Application filed July 30, 1915. Serial No. 42,816.

To all whom it may concern:

Be it known that I, JOSEPH SUTKAY, a citizen of the United States of America, residing at Laurents, in the parish of Vermilion and State of Louisiana, have invented 5 certain new and useful Improvements in Rail-Joints, of which the following is a specification.

This invention relates to new and useful 10 improvements in rail joints.

The primary object of the invention is the provision of an inexpensive connection for the abutting ends of railway rails and whereby the rails are locked together when 15 seated in operative positions upon the ties of the road bed.

A further object of the device is to provide a lock for the adjacent ends of rails which shall be obscure from view and held 20 firmly seated in its operative position by maintaining the adjacent rails upon the railway ties.

A still further object is to provide a combined web and base flange locking connection between the adjacent ends of railway rails and providing for a substantially obscure joint that obviates the requirement of using any bolts or screws for maintaining the rails operatively connected.

With these general objects in view and others that will appear as the nature of the invention is better understood, the same 30 consists in the novel combination and arrangement of parts hereinafter fully described, illustrated in the accompanying drawings and then claimed.

In the drawings forming a part of this application and in which like designating characters refer to corresponding parts 40 throughout the several views: Figure 1 is a side elevation of the end portion of railway rails secured together in the present manner. Fig. 2 is a bottom elevation thereof with the ties and spikes removed. Fig. 45 3 is a transverse vertical section taken upon line III—III of Fig. 1. Fig. 4 is a perspective view of an end of one of the rail sections, and Fig. 5 is a perspective view of the lock block detached.

Referring more in detail to the drawings, 50 end portions 10 and 11 of two adjacent rails of a railway track are herein illustrated mounted in substantially the usual manner upon cross ties 12, the rails being main-

tained in substantial longitudinal alinement 55 by means of the present device.

A double fish plate 13 of H-shape in cross section is adapted to be arranged with its central connecting portion 14 within substantially central longitudinal slots 15 provided in the webs 16 of the said rails. The double fish plate 13 is of sufficient length to receive the slotted portions of the rail web 16 and to seat the ends of the central connecting portion 14 against the ends 17 of 60 the rail slot. Opposite slightly inclined base flanges 18 are provided upon the fish plate 13 adapted to conform to and to rest inclosingly upon the opposite base flanges 19 of the rails and to seat upon the ties 12. 70

Substantially T-shaped sockets or recesses 20 are arranged in the lower face 21 of the rails and adapted for receiving a double headed lock block 22 of the form best illustrated in Fig. 5. 75

When the rails are connected together by means of the fish plate 13, the lock block 22 is positioned in the bottom sockets 20 in the manner illustrated in Fig. 2 and the rails are then flatly positioned upon the 80 ties 12 with the fish plate 13 supported by adjacent ties, while one of the ties completely closes the co-operating recesses 20, thereby retaining the lock block 22 operatively positioned therein when the rails 85 are assembled as best illustrated in Fig. 1, it being understood that any desired number of spikes 23 are employed for securing the members upon the ties by engaging the opposite edges of the fish plate flanges 18 90 or the base flanges 19 of the rails. The recesses 20 are slightly larger than the opposite substantially semi-circular heads 24 of the lock block 22 which allows for the expansion of the metal during the locking engagement of the block, it being seen that the shoulders 25 of the block heads 24 engage the base portions 26 of the recesses 20. 95

It will thus be evident that an inexpensive rail joint is provided which securely 100 locks the rails in operative alinement when the rails are secured to the ties of the road bed.

While the form of the invention herein shown and described is what is believed to 105 be the preferred embodiment thereof, it is nevertheless to be understood that minor changes may be made in the form, propor-

tion and details of construction without departing from the spirit and scope of the invention as claimed.

What I claim as new is:—

- 5 A device of the class described comprising cross ties, rails positioned in alinement and mounted upon the said ties and having horizontal alining slots in their adjacent ends, a double fish plate slidingly positioned
10 within the said slots in flat engagement with the webs of the rails and inclosing the base flanges thereof, retaining means be-

tween the said fish plate and ties, the under faces of the adjacent rails being provided with substantially T-shaped recesses in 15 alinement with each other and a lock block having substantially semi-circular opposite heads of less diameter than the said recesses and engagingly seated therein and flatly positioned upon one of the said supporting ties closely arranged beneath the said recesses. 20

In testimony whereof I affix my signature.
JOSEPH SUTKAY.
